UNITED STATES PATENT OFFICE.

FRANK L. HUTCHINSON, OF MILWAUKEE, WISCONSIN, ASSIGNOR TO HEATING & POWER APPLIANCE COMPANY, OF MILWAUKEE, WISCONSIN, A CORPORATION OF WISCONSIN.

STEAM TRAP.

Application filed March 20, 1922. Serial No. 545,160.

To all whom it may concern:

Be it known that I, FRANK L. HUTCHINSON, a citizen of the United States, and resident of Milwaukee, in the county of Milwaukee and State of Wisconsin, have invented new and useful Improvements in Steam Traps, of which the following is a description, reference being had to the accompanying drawings, which are a part of this specification.

This invention relates to improvements in steam traps and particularly to a device of this type, adapted to be connected to radiators to control the flow of steam or vapor to the radiator and to further control the discharge of the water of condensation therefrom.

This invention contemplates the provision of means whereby the control of the steam is automatically regulated during the discharge of the water of condensation and furthermore provides means whereby the accumulated water of condensation is automatically and periodically discharged when a sufficient amount thereof has accumulated.

This invention further embodies means whereby accumulated air in the radiator may be forced out of the same upon the entrance of steam into the radiator, the said air being discharged through a special passageway provided for that purpose. Another feature of this improved construction is the means whereby the flow of steam may be manually regulated without destroying the automatic means forming one of the primary features of construction.

One illustrative example of this invention is shown in the drawings and described in the accompanying specification so that those skilled in this particular art may readily appreciate the advantages derived therefrom, but it should be understood that while one physical embodiment is illustrated, the invention is capable of application to various modifications of the structure illustrated, without departing from the spirit and scope of the same.

In the drawings:

Figure 1 is a plan view of the valve and steam trap structure with the top cap thereof removed.

Fig. 2 is a vertical section through the device on the plane indicated by 2-2 in Fig. 1; and

Fig. 3 is an enlarged vertical section, partly in elevation, taken on the plane indicated by line 3-3 in Fig. 1.

Referring now, particularly, to the drawings wherein like reference characters represent like parts, the reference character 10 indicates a casing, threaded as at 11, having connection to the bottom of the radiator. The inlet port 12, is connected to a suitable source of steam or vapor supply and the inlet passage is composed of a pipe section 13, in which there is disposed a butterfly valve 14, whereby the supply of steam, which is to be admitted to the radiator, may be controlled. The inlet passageway further comprises a conduit 15, communicating with the pipe section 13, and in turn communicating with the steam chamber 16, formed by the casing. A pipe connection may be made with an outlet 17, for conducting steam into the radiator when the device is used in connection with radiators of large dimensions.

The large threaded pipe 11, by which the main connection with the radiator is accomplished, provides means for the return of the waters of condensation through a passageway 18, formed in the casing 10. Threaded into the lower end of the casing 10 is a plug 19, the upper end of which is formed into a valve seat for the reception of the ball valve 20. Suitable space is provided around the valve plug 19, whereby the waters of condensation accumulate and thereupon raise the ball valve 20 to permit these waters to pass into a water chamber 21; the valve plug 19, may be provided with openings 22, for this purpose.

Mounted within the casing 10 is a float valve 23, guided on a hollow valve stem 24, which in turn carries a valve 25, controlling the water outlet passage, 26. The valve stem 24, is provided with a central passageway 27 with its apertures near the upper end thereof, the lower end of the valve stem being open. The wall of the casing 10, leading to the passageway 18, is pierced as at 29, whereby accumulated air in the radiator, which is displaced by the entrance of steam therein, may be forced out of the radiator through the openings 29, into the apertures 28, and through the hollow valve stem 24, and thence out through the water discharge opening 26. Thus, it will be seen that accumulated air may be ejected from

the radiator without in any manner affecting other operations of this improved device.

Suitably secured to the casing 10 is a bracket 30, upon which there is pivotally supported as at 31, a lever 32, pivoted adjacent one end thereof to the link 33, connected to the float 23. The lever 32, has connected thereto a trip weight 34, this connection being pivotal, a collar 35, being formed on the stem of the trip weight.

The valve stem 24, is provided with a collar 36, which is adapted to be engaged by a lever 37, formed with the stem of the trip weight. Therefore as the float 23, ascends, the lever 32, is rocked, this rocking motion in turn swinging the trip weight 34, to the left, past the center, whereupon it drops to the position illustrated in Fig. 2 and moves the lever arm 37, which in turn engages the collar 36 of the valve stem 34, lifting the valve 25 from its seat and permitting an escape of the water of condensation.

The upper end of the valve stem 24, is provided with a head 38, which is engaged by a swinging latch 39, pivotally supported within the casing 10. The latch 39, swings by gravity to engage the head 38 when the valve stem 27, has been moved past the same. A cam 40, formed on the weight 34, engages the latch 39 when the trip weight has been swung toward the right, thereby moving the latch 39 from engagement with the head 38, and permitting the valve to descend. The lever 32, is provided with a weight 41 to counterbalance this lever.

For manually operating the butterfly valve 14, there is provided a handle 42, connected to a lever 43, one end of which is connected to the butterfly valve while the other end is connected to an adjustable connecting rod 44. Obviously therefore, by properly manipulating the handle lever 42, the butterfly valve may be adjusted and the amount of steam regulated. However, this adjustment in no way affects the operation of the automatic means for opening and closing the butterfly valve.

The plug 19, which as hereinbefore stated, is removable, enables the sediment and the like to be cleaned out of the bottom of the casing 10, and hence no sediment will form on the valve seat carried by this plug, which would, in any manner, affect the proper seating of the ball valve 20.

Inasmuch as the ball valve 20 seats on a plane below the bottom of the radiator and hence operates to permit the water of condensation to escape as it accumulates around the plug 19, no water will be permitted to accumulate in the bottom of the radiator.

The operation of this improved device will be apparent without a further detailed description of the same and by the use of such

a device the automatic control of the steam and the disposition of the water of condensation is accomplished.

While one physical embodiment of the invention is illustrated herein so as to enable those skilled in the art to understand the advantages of the invention, it will be obvious that various changes in form and design may be made without departing from the spirit and scope of the invention.

What is claimed is:

1. In a device of the class described, a casing connected to a radiator, a valve for controlling the passage of steam from the source of supply, an exit for the water of condensation, and means operated by the accumulated water of condensation for opening said exit and controlling the passage of steam.

2. In a device of the class described, a casing adapted to be connected to the lower end of a radiator, a conduit for steam in said casing and connected to a source of supply, a valve in said conduit for controlling said steam, a chamber for the water of condensation, an exit for the water of condensation and a valve for controlling said exit, and means operated by the water of condensation for controlling said steam valve and said water exit valve.

3. A valve device and steam trap for use in combination with a radiator comprising a casing adapted to be connected to the bottom of a radiator, a steam passageway in said casing connected to a source of steam supply, a valve for controlling the passage of steam, a chamber for the water of condensation, a valve means for controlling the passage of said water of condensation to said chamber, an outlet for said chamber, a valve for controlling said outlet, and a float actuated means operatively connected to said steam controlling valve and said last mentioned valve, whereby an accumulation of the water of condensation will cause said steam controlled valve to be closed and said last mentioned valve to be opened.

4. In a valve device of the class described, a casing adapted to be connected to the bottom of a radiator, a steam conduit in said casing connected to a source of steam supply, a valve in said conduit, a chamber in said casing for the water of condensation, a valve controlled passageway for conducting the water of condensation from the radiator to said chamber, a water exit, and a valve controlling said exit and means operated by the accumulation of the water of condensation for closing said steam conduit valve and opening said water exit valve, said means retaining said water exit valve open until the water of condensation has been entirely discharged.

5. In a valve device of the class described, a casing adapted to be connected to the bot-

tom of a radiator, a steam passageway in said casing connected to a source of steam supply, a valve for controlling the passage of steam through said passageway, a chamber formed in said casing, a valve controlled passageway for conducting the water of condensation to said chamber, an outlet for said chamber, a valve controlling said outlet, a float displaceable by the water of condensation, means operated by said float for opening and closing said steam controlled valve and said water valve, said means embodying a latch for retaining said water outlet valve open until all the water of condensation has been discharged, and manually controlled means for operating said steam controlled valve.

6. The combination with a radiator of a steam trap and valve controlling device, comprising a casing adapted to be connected to the lower end of a radiator, a steam passageway through said casing, a valve controlling the passage of steam through said

passageway, a chamber formed in said casing for the water of condensation, a passageway for conducting the water of condensation from said radiator to said chamber, a removable plug positioned in said passageway, and formed with a valve seat, a float valve positioned on said seat, a water exit for said chamber, a valve controlling said water exit, said valve being provided with a hollow stem and apertures therein, a passageway formed in said casing whereby air displaced from said radiator may escape through said casing and hollow valve stem to said water exit, a trip weight, means connecting said trip weight to said steam controlling valve, means on said valve stem and engageable by said trip weight for raising said water exit valve, a float for operating said trip weight, and a latch for holding said water exit valve in open position, said latch being released by said trip weight.

In testimony whereof, I affix my signature.
FRANK L. HUTCHINSON.
